L. A. THOMAS

WINDOW CONSTRUCTION

Filed Sept. 25, 1923

Inventor;
Louis A. Thomas,

8.1.15

per Arthur J. Farnsworth.
Attorney.

UNITED STATES PATENT OFFICE.

LOUIS A. THOMAS, OF LOS ANGELES, CALIFORNIA.

WINDOW CONSTRUCTION.

Application filed September 25, 1923. Serial No. 664,695.

To all whom it may concern:

Be it known that I, LOUIS A. THOMAS, a citizen of the United States, residing at Los Angeles, in the county of Los Angeles and State of California, have invented a new and useful Window Construction, of which a specification is set forth below:

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to window construction and its salient objects are: First, to provide a double hung window permitting of 100% opening; second, to avoid the necessity for using counter-weights or providing space for this purpose; third, to afford facilities for using a single runway for both sash of the window, so as to permit of installing the latter in relatively thin walls; fourth, to furnish means for making such a window water-tight and draft-tight when closed; and, fifth, to accomplish the above objects by a simple and relatively inexpensive construction that is adapted to the requirements of the building arts.

My objects are attained in the manner illustrated in the accompanying drawing, in which—

Figure 1 is a vertical cross section of a complete installation of my improved window construction, the window being fully closed;

Figure 2 is a vertical cross section of the lower portion of the above construction with the window fully open, this view being drawn to a larger scale;

Figure 3 is a sectional plan view of one side of the construction, taken on the line 3—3 of Fig. 1 and drawn to the same scale as Fig. 2; and

Figure 4 is a sectional elevation of one side of the construction, taken on the line 4—4 of Fig. 1, and drawn to the same scale as Figs. 2 and 3.

Similar reference numerals refer to similar parts throughout the several views.

In my construction the upper sash 5 and

lower sash 6 are made closely similar in weight and dimensions. Both of these are hung at each side by a sash cord, or chain, suspended from a pulley adapted to rotate in a plane perpendicular to the sash, one of these pulleys being shown at 7 in Fig. 1. One end of each of the sash chains, as 8, is attached to the lower part of the upper sash; and the other ends of the chains, as 9, are attached to the upper part of the lower sash. Thus, when the upper sash is raised the bottom sash is lowered, and vice versa. Being closely alike in weight, each sash counterbalances the other, and they will remain in equilibrium in any position.

The framing of the window opening, as indicated in Fig. 1, is so arranged that the upper sash can disappear in the wall above the opening. Similarly, the lower sash can disappear in the wall below the opening. The pulley stiles, of which one is shown at 10, are provided with vertical beads 11, and these, in cooperation with the inner and outer jambs 12 and 13, provide slots 14 for the two parts of the sash chains to work in. These beads and jambs also serve as guides for the sash. The beads are not continuous, but are cut away where necessary to provide space for the installation of the sash pulleys and the pivoted sill that will be described.

The meeting rails of the sash are adapted to overlap when the window is closed and I prefer to shape the rail 15 of the lower sash as shown in Fig. 1, with a drip bead 16 spaced from the sash.

Below the window opening my construction provides a pivoted metal sill adapted for retraction into a space 17 below stool 18, when the window is open, and for making a weather-tight joint between the lower sash and outer fixed sill 19 when the window is closed. This pivoted sill comprises a curved apron 20 with an upwardly extending flange 21 at its rear, an upwardly extending flange 22 at each end, and a central downwardly extending flange 23 beneath it. At each end there is a downwardly extending arm 24 by means of which this sill is pivotally mounted upon pivot plates 25 attached to the stiles of the window frame.

Intermediate the ends of the pivoted sill is a web 26 into which the operating rod 27 is hooked. This rod extends through apron 28 and has a convenient terminal 29 for operating it. A compression spring 30 sur-

rounds the operating rod and tends to force the pivoted sill outward when the window is closed as in Fig. 1.

In order to open the window the rod 27 is pulled outward from the apron and the pivoted sill is drawn backward thereby into space 17 as shown in Fig. 2. The lower sash may then be lowered. When this sash is raised again to the closed position the spring forces the pivoted sill outward and effects a weather-tight closure, the lower ends of jambs 13 being recessed at 31 to accommodate the end flanges of the pivoted sill.

I desire to point out that my construction requires the use of but two sash pulleys and two chains for a double hung window, and that the usual counterweights are completely eliminated. I also wish to emphasize its adaptability for thin walls and the fact that it permits of a full 100% window opening.

I wish to be understood that the use of the word "chains" in the appended claims signifies and includes such obvious equivalents as cords, wires, or bands, known in this art.

I claim as my invention:

1. Window construction comprising; opposed sashes, vertically slidable in opposite directions, and suspended at each side of the window by a single chain over a pulley that is perpendicular to the sash plane; and sash pockets above and below the sashes; said pulleys and chains being recessed in the sash guideways to permit free movement of the upper sash; and the sashes having meeting rails adapted for mutual rabbeted engagement.

2. Window construction comprising; opposed sashes, vertically slidable in common guideways in opposite directions, and suspended at each side of the window by a single chain over a pulley that is perpendicular to the sash plane; and sash pockets above and below the sashes; said pulleys

and chains being recessed in the sash guideways to permit free movement of the upper sash; and the sashes having meeting rails adapted for mutual rabbeted engagement and for shedding water outside the plane of the sashes.

3. Window construction comprising; opposed sashes of substantially equal weight, vertically slidable in common guideways in opposite directions, and suspended at each side of the window by a single chain over a pulley that is perpendicular to the sash plane; sash pockets above and below the sashes; and means for making a weather-tight closure between the lower sash and the window sill; said pulleys and chains being recessed in the sash guideways to permit free movement of the upper sash; and the sashes having meeting rails adapted for mutual rabbeted engagement, and embodying a drip bead adapted for shedding water outside the plane of the sashes.

4. Window construction comprising; a sash lowerable into a pocket; and a pivoted sill having upwardly extending flanges at its ends and inner side, adapted to swing outwardly below said sash to intern the bottom edge thereof and make a weather-tight closure between it and the stationary sill; said pivoted sill being mainly concealed within the window casing and adapted for operation by means extending inwardly therethrough.

5. Window construction comprising; a sash lowerable into a pocket; and a pivoted sill having upwardly extending flanges at its ends and inner side, and spring-constrained to swing outwardly below said sash to intern the bottom edge thereof and make a weather-tight closure between it and the stationary sill; said pivoted sill being mainly concealed within the window casing and adapted for retraction by means of a pull rod extending inwardly therethrough.

LOUIS A. THOMAS.
